LINK CHAIN FOR A BRACELET OR THE LIKE

Emil Rodriguez, New York, N.Y., assignor to Jacoby-Bender, Inc., Woodside, N.Y., a corporation of New York

Filed Nov. 21, 1961, Ser. No. 67,640

Term of patent 7 years

(Cl. D45—4)

FIG. 1

FIG. 2

FIG. 3

FIG. 1 is a top plan view for a link chain for a bracelet showing my new design;

FIG. 2 is a side elevational view of the link chain of FIG. 1; and

FIG. 3 is an end elevational view of the link chain, taken from the left-hand end of FIG. 1.

I claim:

The ornamental design for a link chain for a bracelet or the like, as shown.
